UNITED STATES PATENT OFFICE.

HERMAN PROPP, OF OSHKOSH, WISCONSIN, ASSIGNOR OF ONE-HALF TO LEWIS KOSSEL,
OF OSHKOSH, WISCONSIN.

OUTRIGGER FOR BOATS.

967,669.

Specification of Letters Patent. Patented Aug. 16, 1910.

Application filed January 26, 1910. Serial No. 540,241.

To all whom it may concern:

Be it known that I, HERMAN PROPP, citizen of the United States, residing at Oshkosh, in the county of Winnebago and State 5 of Wisconsin, have invented certain new and useful Improvements in Outriggers for Boats, of which the following is a specification.

My invention relates to improvements in 10 outriggers for boats and one of the objects of my invention is to provide an outrigger that shall be noiseless.

A further object of my invention is to provide a removable outrigger, and a socket 15 member permanently attachable to the boat.

A further object of my invention is to provide a circle socket that shall be adapted to receive a corresponding rigger-bar with a circle bearing so as to bind on the circle 20 and thereby prevent wear and noise.

A further object of my invention is to provide a rigger-bar with a shoulder, bearing laterally against the lugs of the socket member to avoid lateral motion and wear.

25 My invention consists essentially of a socket member attachable permanently to the boat and outrigger adapted to lock into the socket member.

In the accompanying drawing Figure 1 30 represents a plan view, Fig. 2 an end view and Fig. 3 a side view of my invention. Fig. 4 represents a bottom view of the rigger-bar.

Similar letters refer to similar parts throughout the several views.

35 A represents the plate of the socket member attachable to the gunwale of the boat, B, B, represent vertical lugs integral with the plate A, each lug being provided with an opening at I and a circular seat C.

40 D represents the rigger-bar and E the rigger-arm.

F represents the oar-lock socket.

The rigger-bar D is provided with semi-circle-bearings G, G, upon each end adapted to seat in the parti-circular seats C, C of the lugs B, B, and a shoulder H is provided at each end of the rigger-bar D adapted to impinge against the inner face of each lug when the locking is completed. The bearing 45 members G—G are formed semi-circular on one side for fitting into the parti-circular seats or sockets C—C, and are flat on the opposite side so as to fit against lugs B—B. The openings I, I are so positioned

and are of such construction between the 55 points of the openings as to permit the circle ends G, G, to slide between them and become closely seated against the circle seats C, C, so as to bind in the operation of locking the outrigger to the socket member. A 60 binding effect is produced in the circular seating of the out-rigger which avoids noise and wear.

A turn-button J may be used to retain the binding of the out-rigger against any possible release.

In the locking operation the rigger-bar bearings G, G, are inserted through the openings I, I and permitted to drop and slide to the circle seats C, C. They take 70 their place in a binding position, the shoulders H, H, impinging against the inner faces of the lugs B, B. The turn-button J may then be turned to impinge against the top of the rigger-arm E to retain the binding 75 position.

Having thus described my invention what I claim is:—

1. An outrigger for boats comprising a plate, a pair of socket members extending at 80 right angles therefrom formed with a socket defining a substantially semi-circular opening, an arm extending at an angle from said plate and formed with a socket for receiving an oar guiding member, and a 85 transverse bar secured to said arm for engaging said sockets, and a binding lever arranged to be moved over said transverse bar for locking the same in said sockets.

2. An outrigger for boats comprising a 90 plate, members extending therefrom formed with semi-circular sockets, and a projecting member extending partially over said sockets, an arm for supporting the oars extending outwardly from said base and 95 formed with journal members having a semi-circular portion and a flat portion, said semi-circular portion fitting into said semi-circular socket, and said flat portion fitting against said over-hanging projection, and a 100 turn-button for locking said journal members in position.

In testimony whereof I affix my signature, in presence of two witnesses.

HERMAN PROPP.

Witnesses:

LEWIS KOSSEL,
A. R. WATERHOUSE.
